CLAIM

An ornamental design for a dental pliers shield, as shown and described.

DESCRIPTION

FIG. 1 is a perspective view of a dental pliers shield showing my new design, on an enlarged scale;

FIG. 2 is a top plan view thereof;

FIG. 3 is a right side elevational view thereof, the left side being a mirror image;

FIG. 4 is a rear elevational view thereof;

FIG. 5 is a front elevational view thereof; and,

FIG. 6 is a bottom plan view thereof.
